UNITED STATES PATENT OFFICE.

GRANT H. TOMB, OF SLATE RUN, PENNSYLVANIA, ASSIGNOR OF ONE-HALF TO JACOB G. TOMB, OF SLATE RUN, PENNSYLVANIA.

RAILROAD-TIE.

1,381,441.

Specification of Letters Patent. Patented June 14, 1921.

Application filed March 9, 1921. Serial No. 451,006.

To all whom it may concern:

Be it known that I, GRANT H. TOMB, a citizen of the United States, residing at Slate Run, in the county of Lycoming and State of Pennsylvania, have invented certain new and useful Improvements in Railroad-Ties, of which the following is a specification, reference being had to the accompanying drawings.

10 It is the purpose of the present invention to provide a tie constructed of relatively heavy sheet metal in one piece, tubular and rectangular in form and provided with a central opening through which the ballast 15 of the road bed engages, in order to anchor the tie in position, there being wood or other fiber supporting base blocks for the rails carried by the tie.

Another purpose is to provide a tie of 20 this character which will facilitate the construction of a railway, and also the repairing of the same, since a workman can very quickly and easily remove the wood or fiber base blocks, so that others can be inserted.

25 Furthermore, the wood or fiber base blocks may be treated with some suitable water proofing material, such as oil or the like, so as to resist the decay of the blocks and permit them to last for a considerable length 30 of time.

Still another purpose is to provide means on the interior of the hollow rectangular tie to prevent the moisture which may enter the central ballast filled opening of the tie, 35 from reaching the wood blocks.

A further purpose is the provision of a tie, wherein the central part of the tie is relatively yieldable or pliable, so that the end portions of the tie may give coincident 40 to the weight of the rolling stock. It has been found that in a tie of this character it is comparatively easier to remove a tie of this construction and place another in position without materially disturbing the 45 road bed, than is possible with the ordinary tie, which has to be dug up from the road bed. Furthermore the wood or fiber base blocks may be very easily and quickly removed, without disturbing the construction 50 of the road bed.

While the design and construction at pres-

ent illustrated and set forth may be deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features 60 and combination of parts, as will be herein-after set forth, shown in the drawings and claimed.

In the drawings:—

Figure 1 is a view in perspective of the 65 improved tie constructed in accordance with the invention.

Fig. 2 is a longitudinal sectional view on line 2—2 of Fig. 1.

Fig. 3 is a cross sectional view on line 3—3 70 of Fig. 1.

Fig. 4 is a detail view.

Referring to the drawings, 1 designates the body of the tie as a whole, and which is constructed of relatively heavy sheet 75 metal, therefore it is not only capable of assuring strength and rigidity, but also assuring resiliency or yieldability at its central portion, whereby the ends of the tie may give incident to the weight of the rolling 80 stock.

The tie is rectangular and tubular in form, and is provided with transverse central openings 2, through which the ballast or the road bed engages in order to anchor the tie in 85 position. The upper and lower walls 3 and 4 of the tie are sufficiently pliable or flexible, to permit the end portions of the tie to yield incident to the weight of the rolling stock. The upper and lower walls 3 and 4 are connected by means of a division wall 5, which may be riveted or otherwise connected to the walls as shown, as by welding in the usual manner or by means of spot welding, or riveted. However, if the tie is constructed of malleable iron or malleable steel in sheet form, in fact cast of such material, the wall 5 may conform with the upper and lower walls 3 and 4.

The end portions of the tie, which are 100 also hollow and rectangular in construction receive wood or fiber rail supporting base

blocks 6, which may be treated with some suitable water proofing material, such as oil or the like, to preserve the blocks for a considerable length of time and resist decay or 5 rotting. The upper parts of the side and the top wall of the tie adjacent both ends thereof are cut away, thereby providing recesses 7, which permit the rails to rest upon the fiber blocks. The blocks or bases are 10 fastened in position by means of screws 8 (which engage through the upper wall of the tie and partly into the bases or blocks) and the bolts 9 (which extend through the upper walls of the tie, entirely through the bases or blocks, and then through the bottom walls of the tie), to insure holding the bases or blocks in position.

In producing a tie of this character, it entirely eliminates the use of clamps or 20 special devices, for holding the rails to the tie. In fact the rails, as shown at 10 are secured to the bases or blocks in the usual manner, as for instance by means of spikes 11.

25 In order to incline the rail in the curve of the track, it depending upon the direction of the curve, the upper face of one of the blocks or bases is recessed or cut away by means of an adz or other suitable tool, for 30 positioning the rail according to the curvature of the track. In short the upper base of the recess or cut away portion of the block is inclined, so as to incline the rail.

In order to separate the central space of 35 the tie from the spaces which receive the bases or blocks, the interior of the tie is provided with partition walls 12, which may be welded by the usual method, or spot welded or otherwise secured in position. By 40 means of these walls 12, it will be noted that the moisture which may enter the central pocket or space adapted for the reception of the ballast, will be prevented from entering the pockets or spaces which contain the 45 rail bases or rail supporting blocks. In fact the only place where the moisture may enter the pockets is where the upper parts of the blocks or bases are exposed, adjacent the recesses of the upper walls of the tie, 50 and if treated with some suitable water proofing solution, it is possible to prolong the life of the blocks, as the water proofing material will resist the weather and thereby prevent the blocks from decaying or rotting.

55 As the upper and lower walls of the central portion of the tie are pliable, the end portions of the tie are capable of yielding or giving, and in such wise as not to materially affect the road bed.

60 In the old construction of a railroad tie, it is difficult to reconstruct the road bed as well as jacking up the tie to permit the road bed to be built up. In repairing the ordinary road bed it is more or less necessary to move the ties, to build up the bed

and insert new ties. Also by means of the central opening receiving the ballast of the road bed, keeps the tie in position, as well as solid, and at the same time prevents the ties from moving laterally, hence avoiding the tracks getting out of alinement. There is a disadvantage in using a solid tie or casting, in that it is very difficult and hard to keep the tracks in alinement, as well as keeping the solid tie in position.

In a tie of the present character, it is possible for a single man to repair several ties, say for instance five or six ties by changing the blocks and arranging the ties in a very short time say for instance a day or 80 probably less, whereas in changing all wood ties, as in the old construction, it is quite a tedious piece of work, and takes considerable time. In fact the all wood tie must be dug up, and this spoils the road bed, and 85 then it takes considerable time in getting the road bed solid again, in order to support the tie. As previously stated in this form of tie, the road bed does not need to be disturbed, it only being necessary to pull 90 or remove the spikes, and loosen the screws or bolts, lift the rail, and thus remove the bases or fiber blocks, so that others may be inserted. The fiber blocks may be constructed of any suitable material, for instance any suitable wood, and may be constructed in any proportion suitable for the purpose. It has been found in the construction of a tie of this character, it is further possible to construct a relatively small size 100 tie, and yet provide as much support and durability to the rails, as in the case of all wood ties. A certain amount of the ballast or road bed may engage within the ends of the tie, acting to more securely hold the tie 105 in position.

The bolts 9 are inserted downwardly through the upper wall of the tie, through the wood or fiber rail supporting base blocks 6, and have their lower ends threaded in the 110 lower wall of the tie, so as to hold the parts together. It is obvious that the bolts may be removed by unscrewing them from their upper portions, permitting the wood blocks to be withdrawn, and replaced by others, 115 without disturbing the position of the tie.

The invention having been set forth, what is claimed as being useful is:

1. A railway tie, comprising a tie body constructed of relatively heavy malleable 120 sheet metal, said body having a central opening provided with upper and lower pliable walls, said body having end pockets with rail supporting fiber blocks therein, the upper parts of the tie being cut away to expose the blocks, whereby the rails may engage therewith.

2. A railway tie, comprising a tie body constructed of relatively heavy malleable 125 sheet metal, said body having a central open-

ing provided with upper and lower pliable walls, said body having end pockets with rail supporting fiber blocks therein, the upper parts of the tie being cut away to expose the 5 blocks, whereby the rails may engage therewith, and means for separating the pockets from the central opening and preventing

moisture from passing from the central opening to the pockets, means for securing the blocks in place.

In testimony whereof I hereunto affix my signature.

GRANT H. TOMB.
